ATTORNEY.

UNITED STATES PATENT OFFICE.

JOHN G. ROPIAK, OF CHICAGO, ILLINOIS.

CONTROL-GLOVE.

1,391,210.

Specification of Letters Patent. Patented Sept. 20, 1921.

Application filed October 15, 1920. Serial No. 417,168.

To all whom it may concern:

Be it known that I, JOHN G. ROPIAK, a citizen of the United States, residing at Chicago, in the county of Cook and State of Illinois, have invented certain new and useful Improvements in Control-Gloves, of which the following is a specification.

This invention relates to gloves, and is especially adapted for use by motormen, engineers, etc., who find it necessary to use a protector for the palm of the hand in the summer as well as the winter, in order that they may more aptly discharge the duties of their positions.

An object of this invention is to provide a hand covering which will permit ventilation of the hands of the user, but which nevertheless adequately covers and protects the portions of the hands and fingers which come in contact with various objects in the line of duty, such for instance as control levers, brakes, etc.

The above and other objects of this invention will be in part described and in part understood from the following description of the present preferred embodiment of the invention taken in connection with the accompanying drawings, wherein:

Figure 1, is an elevational view of the side of the glove constructed in accordance with my invention.

Fig. 2, is a longitudinal sectional view thereof taken on the line 2—2 of Fig. 1, and

Fig. 3, is a sectional view taken on the line 3—3 of Fig. 1.

In the drawings, a palm engaging body 4 is shown which is preferably made of leather, although any other suitable material may be used if desired. The outer end of said body 40 tapers as indicated at 5, while the opposite end has portions of its lateral margins reduced as indicated at 6. A finger stall is provided upon the body 4 by securing a blank sheet 7 on the outer end of the latter.

The blank 7 conforms to the configuration of the body 4, and is secured to the latter by stitches or otherwise thereby causing the tapered outer end of said body to be flexed upwardly toward the blank 7 as indicated at 8 and shown to advantage in Fig. 2. A thumb

50 stall 9 is arranged on the inner face of the

body 4 in proximity to one of the reduced margins 6. This stall is likewise formed from a blank, having one end thereof secured to the body 4, and one side thereof turned over into parallelism with the opposite side and stitched or otherwise fixedly secured thereto. It will be noted that one of the sides of the thumb stall is extended to provide a tab which is engaged with the body 4, the opposite side terminating approximately at the margin of the body 4 which the thumb stall overlies. A wrist engaging band 10 is provided, one end of which is equipped with a buckle 11 for engagement with the free end of the strap. The strap is provided with a stud for engagement with a corresponding socket 12 which is mounted in the body 4 in proximity to the inner end thereof.

It will be understood from the above that the finger stall is so arranged and of such a size that only the outer ends of the fingers will be engaged. This is likewise true of the thumb stall, consequently, the hand is left exposed, except to the extent stated. By providing the finger stall, thumb stall, and strap 10, the glove will be securely held on the hand of the wearer. By making the body portion 4 flat, ventilation will be permitted therebetween and the palm of the hand when the operator disengages his hand from the lever or other object with which it has been engaged. Various changes may be made in the shape, size, and materials used without departing from the spirit and scope of this invention as covered by the appended claim.

What is claimed is:

A glove including a flat palm engaging body, a blank engaged across one end of the body with its margin secured to the margin of the body to provide a single stall for the reception of the tip ends only of all of the fingers, and a second blank secured to said body reversely folded upon itself, and the marginal edges thereof secured to provide an inclosed thumb stall.

In testimony whereof I affix my signature in presence of two witnesses.

JOHN G. ROPIAK.
